GRIPPING AND LIFTING DEVICE

Filed April 1, 1947

UNITED STATES PATENT OFFICE

2,543,947

GRIPPING AND LIFTING DEVICE

Person A. Thelin, Chicago, Ill.

Application April 1, 1947, Serial No. 738,685

4 Claims. (Cl. 294—104)

1

The present invention relates to an improved gripping and lifting device such as may be employed for the lifting of flat objects as plates, or for the lifting of boxes, shipping cases, etc.

It is one of the objects of the present invention to provide a gripping and lifting device which will be easy to manufacture, will be positive in its action, and will not slip from the object which it is desired to lift.

A further object of the invention is to provide a gripping and lifting device provided with only one movable part which is suitably pivoted to a yoke between the arms of which the article to be lifted is positioned, suitable gripping fingers on the device being brought into contact with the article to be lifted with a pressure which is proportional to the weight of the article.

Other objects will appear from the further description hereinbelow when considered in connection with the concurrently filed drawing in which:

Fig. 1 is a perspective view of the improved gripping and lifting device of the present invention;

Fig. 2 is a side elevational view showing the device in use, and also showing changed position of certain parts thereof in dotted lines;

Fig. 3 is an elevational front view;

Fig. 4 is a plan view, and

Fig. 5 is a perspective view, on a somewhat enlarged scale, of the only movable portion of the device constituting the handle and gripping fingers thereof.

The device of the present invention comprises a substantially U-shaped yoke broadly designated by the reference numeral 6, preferably reinforced by means of an outstanding flange 7, the yoke having two arms 8 and 9, on one of which (9) is mounted a lifting and gripping member 10 which is preferably made in one piece from a heavy rod bent substantially into the loop shape shown in Fig. 5.

The member 10 comprises a handle portion 11, and two substantially semi-circular turns 12 and 13, which connect with substantially straight portions 14 and 15 which are substantially parallel to the portion 11. The portions 14 and 15 terminate in two laterally extending gripping fingers 16 and 17, which are intended to engage against the article to be lifted such as a plate 18 which is positioned between the arms 8 and 9 of the yoke.

The member 10 is pivotally connected to the yoke 6 by means of a plate 19 which is suitably secured, for example by means of the rivets 20, 55

to the arm 9 of the yoke, this plate being cut away so as to form extensions 21 and 22 which are bent into the form of ears or loops through which the portions 14 and 15 of the member 10 extend.

When the yoke is in the vertical position as shown in the drawings, the weight of the member 10 will tend to bring the gripping fingers 16 and 17 into a vertical position, and to insure that they will not move any further than into a parallel relationship with the arms, for example arm 9 of the yoke 6, a suitable stop 23 is provided, which may take the form of a rod which passes through the flange 7 of the yoke.

When using the device, the article to be lifted, such as a plate, or the side of a crate or box, designated 18, is positioned between the two arms of the yoke, whereupon the member 10 is lifted by means of the handle 11, which may be accomplished either by hand or by means of the lifting hook 24 which is suitably suspended from a cable 25 as shown in Fig. 2. The first effect will be to move the member 10 from the position shown in solid lines to the position shown in dotted lines, whereby the gripping fingers 16 and 17 will be caused to engage against the surface of the article 18, thus forcing it strongly against the arm 8 of the yoke. The heavier the article 18 is, the greater will be the force required to lift it, which force being applied to the handle 11 will be transmitted to the fingers 16 and 17, which will firmly press against the article 18 so that the latter will be securely clamped within the yoke.

By reason of the fact that the ends 35 of the gripping fingers 16 and 17 are cut off squarely, these fingers will tend to dig into the article and prevent it from slipping from the yoke. If for example the device is used for the lifting of an iron plate, the latter can safely be lifted without danger of slipping from the yoke.

If on the other hand the article 18 is the side of a box, and by providing two such devices as that shown in the present application, one being applied to each opposing side of the box, the same may then be safely lifted and carried.

It will be obvious that the device can be made in any appropriate size and if made in a small size, the member 10 might well be made of heavy steel wire, while for the larger sizes it is best made from heavy steel or wrought iron rod stock.

When setting the article down and releasing the pull on the handle 10, the gripping fingers 16 and 17 will return to the position shown in solid lines in Fig. 2, in that case abutting against the stop 23, so that the yoke may be freely lifted

from the article which had been gripped within the arms of the yoke.

There is a particular advantage in constructing the gripping and handle member of a single piece as this not only renders it rigid and substantially unbreakable, but also thereby provides a pivot for said member by reason of the fact that the straight portions 14 and 15 pass through the ears 21 and 22.

If desired the flange 7 may be omitted, but as it greatly reinforces the yoke, it is preferably employed.

The device may be manufactured of any suitable metal, but iron or aluminum suggest themselves as the most suitable materials for the purpose.

Applicant claims:

1. A gripping and lifting device comprising a flanged U-shaped straight-sided yoke having two opposed parallel arms having smooth inner surfaces, a transverse plate on one of said arms, ears formed on said plate on each side of said yoke, and a one-piece heavy rod lifting-handle having gripping fingers integral therewith capable of engaging an article positioned between the arms of said yoke, said lifting-handle being pivoted to the yoke by having portions thereof embraced by said ears.

2. A gripping and lifting device comprising a flanged U-shaped straight-sided yoke provided with pivoting ears on each side of one arm thereof, a lifting-handle having gripping fingers extending parallel of said arm, and in substantial alignment therewith, said lifting-handle being pivoted to said arm by having opposed portions thereof passing through said ears, whereby upon lifting of said lifting-handle said gripping fingers will be swung into a plane at an angle to the planes of the arms of the yoke and brought into gripping engagement with an article positioned between said arms.

3. A lifting device comprising a U-shaped grip-

ping yoke having parallel opposed flat inner surfaces and provided with outwardly extending heavy reinforcing flanges to prevent spreading of said yoke when gripping a flat object between its opposed surfaces, a flat plate secured to one leg of said yoke, upwardly extending parts of such plate being curved back upon themselves to provide bearings on each side of a flange, a heavy rod bent into such shape as to provide a lifting handle, two portions thereof being substantially parallel with said handle portion, and two gripping-fingers, said parallel portions passing through the bearings provided on said plate, and a stop abuttable by said fingers and positioned on the same side of said flanges as that on which the plate is secured to prevent the lifting handle from assuming a downwardly depending position when the yoke is disengaged from the article intended to be gripped thereby, so that when the yoke is slipped over the article to be lifted the lifting handle will extend laterally from the side of the yoke for ready grasping by an operator using the device.

4. The device as claimed in claim 3 in which the side of the yoke bearing the plate is longer than the opposed side of the yoke.
